UNITED STATES PATENT OFFICE.

WILLIAM B. BIGELOW, OF NEW YORK, N. Y., ASSIGNOR TO WM. KNABE & CO. MANUFACTURING COMPANY, OF BALTIMORE, MARYLAND.

DESIGN FOR A GRAND-PIANO LEG.

SPECIFICATION forming part of Design No. 21,247, dated December 22, 1891.

Application filed November 17, 1891. Serial No. 412,210. Term of patent 7 years.

To all whom it may concern:

Be it known that I, WILLIAM B. BIGELOW, a citizen of the United States, residing at New York, in the county of New York and State 5 of New York, have invented a certain new and original Design for Grand-Piano Legs; and I do hereby declare the following to be a full, clear, and exact description of the invention, such as will enable others skilled in 10 the art to which it appertains to make and use the same.

My invention relates to an original design for grand-piano legs.

The leading features of my design are an 15 upper portion representing two panels, one within the other and a border within the smaller panel, a central portion representing a series of vertical projections, and a lower portion representing a number of oval panels 20 having a border, scroll-work adjacent to said panels, and a representation of a ring of balls or beads, and disks at the lower end of the lower portion.

The accompanying drawing represents my 25 design.

A represents the upper portion of a grand-piano leg, B the central portion, and C the lower portion. On the outer face of the upper portion is the representation of a panel 30 a, having a border at the ends and lower edge thereof represented by a scroll b. At the center of the panel a is represented a

smaller projecting panel b, within which a decorative border d is represented. Beneath the upper portion A the central portion B is 35 represented as having its circular face made to represent a series of curved projections e, and a series of smaller curved projections f projecting from the projections e, and a series of small flanges g between the larger projections e. Below the central portion B is represented a groove or depression h. The lower portion C is represented as of oblong form and has represented on its outer face a series of oval panels i, and a series of intermediate 40 knobs j, a continuous border k encircling said panels and knobs. Above and below the panels i is represented scroll-work of oval form, and near the lower end of the portion C is a ring of beads or balls and disks l l', the 45 foot of the leg being represented as round and having a series of grooves m therein.

Having fully described my design, what I claim as new and original, and desire to secure by Letters Patent, is—

The design for piano-legs herein shown and described.

In testimony whereof I have signed this specification in the presence of two subscribing witnesses.

WM. B. BIGELOW.
